UNITED STATES PATENT OFFICE.

CHARLES W. HARROLD, OF CLEVELAND, OHIO, ASSIGNOR TO THE HARRIS AUTOMATIC PRESS COMPANY, OF CLEVELAND, OHIO, A CORPORATION OF OHIO.

SHEET GRIPPER.

Application filed March 28, 1924. Serial No. 702,546.

To all whom it may concern:

Be it known that I, CHARLES W. HARROLD, a citizen of the United States, residing in the city of Cleveland, in the county of Cuyahoga and State of Ohio, have invented certain new and useful Improvements in Sheet

5 Grippers, of which the following is a specification, reference being made to the accompanying drawings, forming a part thereof.

10 My invention relates to improvements in the gripping devices usually employed in printing presses for transferring sheets of paper, or stock, from one member to another.

The objects of my invention are, among 15 other things, to provide an improved sheet-carrier mechanism of this character, in which separate pairs of grippers are mounted in spaced-apart relationship on a cross gripper bar, whereby a slip sheet as well as a printed 20 sheet may be seized and carried by my double gripper mechanism, one set of the grippers taking the slip sheet and the other set the main or printed sheet; furthermore to provide novel and effective means to open one 25 set of grippers without disturbing the other set both of which sets are normally maintained in closed position.

A further feature of novelty, more particularly in combination with a chain-delivery, is the provision of improved means embodied with my improved double-gripper mechanism whereby a slip sheet may be advanced to one set of grippers on the delivery-bar and then another sheet (usually a printed 30 sheet) may be thereafter advanced to the same delivery-bar, the double sets of grippers serving to convey such slip sheet and printed sheet in superposed position along the delivery and then dropping both slip and 35 printed sheets on the delivery pile.

40 In the accompanying drawings, Figure 1 shows an end elevation of my improved sheet-gripper mechanism mounted on the usual chain-delivery with the right hand end broken off, such figure illustrating one embodiment of my invention;

45 Figure 2 is an enlarged side view of a pair of grippers mounted on the delivery chains;

50 Figure 3 is an enlarged sectional view taken on the line 3—3 of Figure 1 looking in the direction of the arrows;

Figure 4 is an enlarged sectional view taken on the line 4—4 of Figure 1 looking in the direction of the arrows;

55

Figure 5 is an end view of Fig. 3; and

Figure 6 is an enlarged sectional view taken on the line 6—6 of Figure 1 looking in the direction of the arrows.

Similar numerals refer to similar parts 60 throughout the several figures.

Referring to the drawings, more particularly Figs. 1 and 2, the delivery-bar 7 is suitably mounted in the delivery chains 8 (only one set being shown), and the gripper 65 shaft 9 is journalled at both ends in the brackets 10 mounted on the chains 8 so as to oscillate to open and close the two sets of grippers carried by such shaft 9. Secured to one end of the shaft 9 is the arm 11 (shown in Figs. 1 and 2) carrying the cam-roller 12 which is adapted to ride over the fixed cam 13 to rock the shaft 9 in a clockwise direction in the usual manner to open the grippers.

70 In Figure 1 I have shown two pairs of grippers mounted in spaced-apart position on the shaft 9, and a detailed description of one pair will suffice for both. The shorter or main sheet gripper 14 is mounted with its forked ends around the shaft 9 and is free to rotate thereon; between the forked ends of such gripper 14 is the split collar 15 rigidly affixed to the shaft 9 in any predetermined position by the screw-bolt 16. The collar 15 carries the dog 17 to bear against the shoulder 18 on the under-side of the gripper 14. The coil spring 19 secured between the lug 20 affixed to the gripper 14 and the dog 17 on the collar 15 75 as shown in Figure 5 normally holds the grippers 14 closed against the contact block 22 on the delivery bar 7 with the dog 17 in contact with the shoulder 18 as shown in Figure 4. When the shaft 9 is rocked in a clockwise direction (Fig. 4), the gripper 14 is opened by the dog 17 moving upwardly to the right against the shoulder 18 on the gripper 14.

80 The longer or slip sheet gripper 23 is also mounted with its forked ends around the shaft 9 and is also free to rotate thereon; between the forked ends of the gripper 23 85 is the split collar 24 rigidly secured to the

shaft 9 in any predetermined position by the screw-bolt 25. The collar 24 carries the projecting dog 26 adapted to bear upwardly against the shoulder 27 formed on the under side of the gripper 23 to open the gripper 23 from its closed position on the contact block 28 carried by the delivery bar 7. As shown in Figure 3, when the gripper 23 is closed on the block 28, the dog 26 is not in contact with the shoulder 27. Coiled about the shaft 9 is the torsion spring 29, one end of which is suitably secured to the collar 30, fastened to shaft 9 by set screw 31, while the other end of the spring 29 passes under one of the forked ends of the gripper 23 and bears on the top of the lug 21 on the lower end of the gripper 23. This spring 29 acts to take care of the greater rocking movement of the shaft 9, since the gripper 23 must hold the slip sheet fast against the block 28 when the gripper 14 is opened to seize the main or printed sheet. As shown in Figs. 1, 2 and 3 the slip sheet gripper 23, owing to its position with the contact block 28 on the delivery bar 7 seizes the slip sheet somewhat before the gripper 14 takes the main sheet, when the delivery is moving as shown in Figure 2.

Referring to Figures 1 and 6, the cam-roller 12 is yieldingly held in a depending position ready to snap off the cam 13 (Fig. 2) by the following mechanism: Surrounding the delivery bar 7 is the split collar 32 secured by the screw bolt 33; the collar 32 is connected to the collar 34 journalled on the shaft 9 by the bar 35. The collar 32 carries the depending slotted bracket 36 through which passes the free end of the rod 37 pivoted on the pin 38 secured to the collar 39 rigidly affixed to the shaft 9 by the set screw 40; coiled about the rod 37 is the expansion spring 41 one end bearing against the bracket 36 while the other end is fastened to the collar 39. The force of the spring 41 tends to rock the gripper shaft 9 in an anti-clockwise direction to force the cam-roller arm 11 to approach the vertical when the cam 12 rides off the cam 13.

The operation of my improved sheet-gripper mechanism on the chain delivery 8, when seizing both a slip sheet and printed sheet to thereafter carry same, is as follows: When the delivery chains 8 are passing to the right (Fig. 2) both the gripper 14 and gripper 23 are closed against their respective contact blocks 22 and 28. As the cam-roller 12 rides up the cam 13 the gripper-shaft 9 is rocked in a clockwise direction (Figs. 3 and 4) which movement immediately opens the gripper 14 with the dog 17 lifting against the shoulder 18; as the roller 12 rides on toward the high part of the cam 13, the shaft 9 is further rocked in the same direction against the tension of

the torsion spring 29, which movement brings the dog 26 against the shoulder 27 to lift the gripper 23 off the contact block 28. At this moment a slip sheet is fed to the gripper 23 with the block 22 acting as a stop and the gripper 23 immediately closes on such sheet against the block 28; later on in the cycle, the printed sheet is transferred to the gripper 14 which then seizes such printed sheet, the closing of both grippers being effected through the mechanism actuated by the spring 41 when the roller 12 snaps off the cam 13. Thereafter during the forward run of the delivery chains 8, both slip and printed sheets are carried in superposed position to be thereafter dropped together on the delivery pile.

While the construction herein shown embodies the invention in a preferred form, it will be understood that changes and variations may be made in the various parts without departing from the principles and scope of the invention or sacrificing its chief advantages.

I claim as my invention:

1. A sheet-gripper comprising, a shaft, a pair of gripper fingers mounted thereon and means to actuate same in sequence.

2. A sheet-gripper comprising, a shaft, a pair of gripper fingers mounted thereon and means to actuate same in predetermined sequence.

3. A sheet-gripper comprising, a shaft, a pair of normally closed gripper fingers mounted thereon and means to open same in sequence.

4. A sheet-gripper comprising, a shaft, a pair of normally closed gripper fingers mounted thereon and means to open same in predetermined sequence.

5. A sheet-gripper comprising an oscillatable gripper-shaft, a pair of gripper fingers movably mounted on said shaft, and means to successively actuate said fingers through the movement of said shaft.

6. A sheet-gripper comprising an oscillatable gripper-shaft, a pair of normally closed gripper fingers movably mounted on said shaft, and means to successively open said fingers through the movement of said shaft.

7. A sheet-gripper comprising an oscillatable gripper-shaft, a pair of normally closed gripper fingers movably mounted on said shaft, and means to successively open said fingers through the continued movement of said shaft.

8. A sheet-gripper comprising an oscillatable gripper-shaft, a pair of normally closed gripper fingers movably mounted on said shaft, and means to successively open said fingers through the continued movement of said shaft in the same direction.

9. In combination, a delivery bar, an oscillatable gripper shaft in parallelism there-

with, a pair of gripper fingers movably mounted on said shaft and closed on said delivery bar, and means to successively open said fingers through the movement of said shaft.

10. In combination, a delivery bar, an oscillatable gripper shaft in parallelism therewith, a pair of gripper fingers movably mounted on said shaft and each yieldingly closed on said delivery bar, and means to successively open said fingers through the movement of said shaft.

11. In combination, a delivery bar, an oscillatable gripper shaft in parallelism therewith, a pair of gripper fingers movably mounted on said shaft and each yieldingly closed on said delivery bar, and means to open said fingers in predetermined sequence through the continued movement of said shaft.

12. In combination, a delivery bar, an oscillatable gripper shaft in parallelism therewith, a pair of gripper fingers movably mounted on said shaft and each yieldingly closed on said delivery bar, and means to open said fingers in predetermined sequence through the continued movement of said shaft in the same direction.

13. A sheet-gripper comprising a plurality of gripper fingers and a single means for actuating the several fingers in sequence.

14. In combination, a plurality of grippers, separate sheet supports for each gripper, means for holding each gripper in yielding contact with its support, and a single means for actuating each gripper in predetermined sequence.

15. In combination, a plurality of grippers, separate sheet supports for each gripper, means for holding each gripper in yielding contact with its support, and means for actuating each gripper in predetermined sequence against said holding means.

16. In a delivery, a delivery-bar acting as a support for sheets, an oscillatable gripper-shaft carried by the delivery, a plurality of grippers rotatably mounted on said shaft, means for holding each gripper in individual yielding contact with said support, and means for successively opening said

grippers against said holding means through movement of said shaft.

17. In a delivery, a delivery-bar acting as a support for sheets, an oscillatable gripper-shaft carried by the delivery, a plurality of grippers of varying lengths rotatably mounted on said shaft, means for holding each gripper in individual yielding contact with said support, and means for successively opening said grippers against said holding means through movement of said shaft.

18. In a delivery, a delivery-bar acting as a support for sheets, an oscillatable gripper-shaft carried by the delivery, sets of grippers of different lengths rotatably mounted on said shaft, means for holding each gripper in individual yielding contact with said support, and means for successively opening each set of said grippers against said holding means through movement of said shaft.

19. In a sheet-gripper mechanism, a shaft, separate sets of grippers having different lengths mounted thereon, separate sheet supports for each set, and means for actuating each set of said grippers in predetermined sequence.

20. In a sheet-gripper mechanism, separate sets of grippers having different lengths, separate sheet supports for each set, means for yieldingly holding each gripper on its support, and means for actuating each set of said grippers in sequence against said holding means.

21. In a delivery, a travelling delivery-bar acting as separate sheet supports, separate sets of grippers for seizing separate sheets fed to said supports, and means for opening each set of grippers in sequence thereafter to close on said sheets.

22. In a delivery, a travelling delivery-bar acting as separate sheet supports, separate sets of grippers for seizing separate sheets fed to said supports, and means for opening each set of grippers in sequence thereafter to close on said sheets during the further movement of the delivery.

CHARLES W. HARROLD.
